UNITED STATES PATENT OFFICE

JACOB C. ADDICKS, OF BALTIMORE, MARYLAND, AND WALTER E. BURGESS, OF RUTHERFORD, NEW JERSEY, ASSIGNEES TO THE CENTRAL FOUNDRY COMPANY, OF NEW YORK, N. Y., A CORPORATION OF MAINE

PIPE FLASK

Application filed March 3, 1928. Serial No. 258,807.

Our invention relates to foundry flasks, and particularly to sand flasks used for forming sand mold sections for the casting of a plurality of pipe sections in a single pair of flasks. Our invention also comprises various features which we shall hereinafter describe and claim.

In the accompanying drawings, Fig. 1 is a plan of the drag of a flask embodying our invention; Fig. 2 is a section on lines II—II of Fig. 1 but with the molded sand in position therein; Fig. 3 is a plan of the cope; Fig. 4 is a section on lines IV—IV of Fig. 3; and Fig. 5 is the hub end elevation of an assembly of the cope and drag sections.

Referring more specifically to the drawings, the cope and drag sections 2 and 3 of the flask are preferably made of aluminum and are substantially similar in shape. In each the longitudinally extending sides 4 flare outwardly from the outside surface 5 (the bottom of one section or the top of the other, as the case may be) to the central horizontal plane 6 of the flask, and the portion 7 of the sides 4 away from such central plane 6 is cut away or inclined inwardly at 8 to the longitudinally extending ribs 9 which project beyond the other portions of the flask to form bearings or supports for the two parts 30 of the flask during the mold forming operation and for the drag during the pouring operation. These ribs or bars 9 have tapering sides, which increase in cross-section toward the outer surface 5 of the section, and are so placed that it is not necessary to use the usual bottom boards to hold the sand in the flask, and such ribs 9 may be reduced to a minimum of two, which thus readily afford proper bearings for that flask section when set on the foundry floor. Each flask section has also on its inner surface a plurality of recesses 10, which conform to the exterior of the pipe to be cast. The flasks are reinforced by cross webs 11 which join the ribs 9 and divide the area of the flask into compartments the sides of which afford a bearing for the sand. After being rammed the sand is struck off by the molder to the line indicated at 8, so as to permit the flask to have an uninterrupted and steady bearing upon the bars 9.

Our improved flasks by reason of the flaring or tapered sides 4 are better adapted to be filled by a sand slinging machine than those with straight sides. The flaring or tapered sides 4 also assist in a more proper distribution of the sand by the sand slinging machines, as well as a better support for the sand after it has been rammed and struck off. The cutting down of the extent of the side wall and the elimination of acute internal angles or corners renders the action of the sand slinging machine more effective and also enables the flasks to be rammed to better advantage. The cutting off of the corners of the flask sections also permits the easier rolling over and also the handling of such sections because of the reduction in weight both of sand and of flask. The cutting back of the corners and bevelling of the sand upwardly from the edges of the bars to form the surfaces 8 also gives less surface to encounter projections or irregularities on the foundry floor, and enables the usual bottom boards to be dispensed with. If desired, the flasks may have a sand strip 4^a, as is shown in Fig. 4.

The terms and expressions which we have employed are used as terms of description and not of limitation, and we have no intention, in the use of such terms and expressions, of excluding any mechanical equivalents of the features shown and described, or portions thereof, but recognize that various structural modifications are possible within the scope of the invention claimed.

What we claim is:

1. In a flask for casting multiple pipe, cope and drag sections each having side walls flaring toward the central horizontal plane of the flask, each section having longitudinal ribs intermediate its side walls adapted to rest on the floor to support such section with a portion of its bottom free of the floor.

2. In a flask for casting multiple pipe, cope and drag sections each having side walls flaring toward the central horizontal plane of the flask, supporting ribs for each section intermediate the side walls and adapted to rest on the floor, the surface between a rib and the side wall being inclined upwardly

from the rib to the side wall to reduce the weight of the section and eliminate sharp internal angles.

3. In a flask for casting multiple pipe, 5 cope and drag sections each having side walls flaring toward the central horizontal plane of the flask, supporting ribs for each section intermediate the side walls and adapted to rest on the floor, the surface between a rib 10 and the side wall being inclined upwardly from the rib to the side wall to reduce the weight of the section and eliminate sharp internal angles, the adjacent edges of the side walls terminating at a distance vertically from the horizontal plane in which the outer edges of the ribs lie, said wall and ribs comprising means for supporting molding sand in the flask without bottom boards.

4. In a flask for casting multiple pipe, 20 complementary cope and drag sections each having side walls flaring toward the central horizontal plane of the flask, and ribs arranged at right angles to each other between the side walls dividing the section into rectangular compartments adapted to support the sand in the section certain of the ribs being arranged at their outer ends to support the section on the floor.

5. In a flask for casting multiple pipe, 30 complementary cope and drag sections each having side walls flaring toward the central horizontal plane of the flask, and ribs arranged at right angles to each other between the side walls dividing the section into rectangular compartments adapted to support the sand in the section, some of the ribs extending longitudinally of the flask substantially beneath the axes of the pipe to be cast and being of increasing cross-section toward the outer surface of each such section.

6. In a flask for casting multiple pipe complementary cope and drag sections, each having a plurality of longitudinal ribs extending substantially beneath the axes of 45 the pipe to be cast, and a plurality of transverse partition members having cut-away portions conforming generally to the contour of the pipe to be cast, said ribs and partition members serving to divide said sections into substantially rectangular compartments adapted to hold molding sand.

7. In a flask for casting pipe complementary cope and drag sections each having a longitudinal rib extending substantially 55 beneath the axis of a pipe to be cast and adapted to rest on the floor, and a plurality of partition members extending transversely of each section, said members being cut away to conform to the contour of the pipe 60 to be cast.
